UNITED STATES PATENT OFFICE.

ANDREW GERMEK, OF EDWARDSVILLE, PENNSYLVANIA.

CAR-LOADING MEANS.

Application filed June 5, 1924. Serial No. 718,134.

To all whom it may concern:

Be it known that I, ANDREW GERMEK, a citizen of the United States, residing at Edwardsville, in the county of Luzerne and State of Pennsylvania, have invented certain new and useful Improvements in Car-Loading Means; and I do declare the following to be a full, clear, and exact description of the invention, such as will enable others skilled in the art to which it appertains to make and use the same.

In loading cars with coal from a plurality of elevated pockets along one or both sides of a track, it is customary to have manually opened gates to control the discharge of coal from the pockets into the cars. Hence, a number of attendants are necessary for the numerous gates, but one object of my invention is to provide novel means controlled by compressed air or other fluid under pressure for opening and closing the gates as required, the arrangement being such that one man, controlling the valves of the various pipe lines can open and close any gate or gates at will.

The coal as it is now discharged directly from the pockets into the cars, often overflows from the latter and is not evenly distributed along the length of the cars. It is a further object of my invention to provide chutes into which the coal pockets discharge, said chutes being mounted for upward and downward swinging and having coal distributing scrapers at their discharge ends. These chutes direct the coal into the cars from the pockets, and when any car is moved upon the track after maximum filling of a portion of said car, the scraper comes into play to remove surplus coal and scrape it into the empty portion of the car. Thus, all of the cars may be loaded to the same extent and the loads thereof uniformly crowned to the desired degree.

A still further object of the invention is to connect the chutes and the gates with common operating means, so that when any gate is opened, its respective chute will be automatically lowered to an operative position, return of the chute to a raised position being also effected by closing of the gate.

With the foregoing in view, the invention resides in the novel subject matter hereinafter described and claimed, the description being supplemented by the accompanying drawings.

Figure 1 is a vertical transverse sectional view of a track, coal pockets above and at opposite sides of said track, and the several features of my invention in operative relation with the pockets.

Figure 2 is a vertical longitudinal sectional view as indicated by line 2—2 of Fig. 1.

Figure 3 is a horizontal sectional view partly broken away, as indicated by line 3—3 of Fig. 2.

Figure 4 is a vertical longitudinal section on line 4—4 of Fig. 3.

Figure 5 is a transverse sectional view on line 5—5 of Fig. 3.

Figure 6 is a perspective view showing a portion of the operating means for the gates and the chutes.

In the drawings above briefly described, the numeral 1 designates a track for the cars 2, to be loaded, and at 3, a plurality of coal pockets have been shown, to which coal is fed through the chutes 4. In the arrangement shown, the inner walls 5 of the pockets 3 converge upwardly to a point above the track 1 and said walls 5 are provided with slideable gates 6 controlling the discharge of coal, inclined chutes 7 being shown for guiding this coal toward the center of a car to be filled.

Disposed longitudinally above the track 1, are a plurality of chutes 8 into which the chutes 7 deliver, said chutes 8 being mounted for upward and downward swinging and having downturned discharge ends 9 provided with coal distributing scrapers 10 for disposition in close relation with the car being filled.

Each scraper 10 preferably comprises a pair of substantially horizontal scraping members 11 which are widely spaced at one end to rest on the side walls of a car, while said scraping members converge to a point at their opposite ends. The downturned chute end 9 is received between the two scraping members and secured thereto in any desired manner. I have shown a bolt 12 passing through the chute end 9 and the scraping members 11 and have shown a cross bar 13 whose ends are secured to said scraping members, the intermediate portion of said bar being secured to the downturned ends of the chutes by bolts or the like 14 as seen in Fig. 4. Across the front portion of the chute 8, another bolt 15 has been shown, from which a rod 16 rises, for

upwardly or downwardly swinging the chute and the scraper.

The end of the chute 8 opposite the scraper 10, is pivotally mounted on a transverse axis. In the present showing, a shaft 17 supports said end of the chute 8 and the ends of this shaft are supported by vertical bars 18 which are slidably received in vertical guides 19 suitably supported on part 10 of a framework 20 beneath the pockets 3. I have shown vertically spaced openings 21 in the bars 18, and pins 22 are insertible through any of said openings to engage the upper ends of the guides 19, so as to hold 15 the bars 18 in any positions to which they may be adjusted, according to the height of the cars to be loaded.

Normally, the chutes 8 are raised as shown at the left of Fig. 2, but when they 20 are to receive coal and guide it into one of the cars, any suitable number of said chutes may be lowered as shown at the right hand end of Fig. 2. Thus, coal discharged by one or more of the chutes 7 into the lowered 25 chute or chutes 8, will slide down the latter into the car. For purposes of illustration, we will assume that only one of the chutes 8 has been lowered as seen in Fig. 2. When so lowered, the scraper 10 30 rests on one end of the car and when such end has been filled with coal, the car is moved longitudinally in the direction of the arrow A. As the car moves in this manner, the scraping members 11 will 35 scrape surplus coal off the top of the pile in the car and will discharge it into an un-filled part of the car, at the same time ridging the coal to the desired extent. When another portion of the car is filled, 40 said car is further advanced, and so on until completely filled. It will thus be seen that surplus coal may be removed from any loaded car and that the loads of all of the 45 cars are uniformly ridged.

Novel provision is made for operating the gates 6 and for controlling the upward and downward movements of the chutes 8. In the construction shown, the gates 6 are connected by links 23 with wheels 24 carried 50 by longitudinal shafts 25 which may well be supported by bearings 26 secured to the walls 5 of the coal pockets 3. Other links 27 have been shown connected to and extending upwardly from the wheels 24 to cross arms 28 on vertical piston rods 29, the 55 pistons of these rods being confined in pressure cylinders 30 which are stationarily mounted in any desired manner. I have shown the upper ends of the rods 16 suitably connected with the cross arms 28 and the arrangement is such that when any cross arm is forced downwardly by the admission of compressed air or steam into the upper end of the cylinder 30, the rod 16 lowers the subjacent chute 8 and at the

same time, the links 27 turn the wheels 24, thus pulling upon the links 23 and opening the gates 6. By the time the gates open sufficiently to permit any appreciable discharge of coal, the chute 8 has lowered to 70 operative position and guides such coal into the car to be loaded. Whenever the cross head 28 is raised by admission of pressure into the lower end of the cylinder 30, the gates 6 are automatically closed and at the 75 same time, the rod 16 restores the chute 8 to its original raised position.

Leading to the upper end of each cylinder 30, is a pipe 31 while another pipe 32 leads from the lower end of said cylinder. These 80 two pipes connect with what is commonly known as an engineer's valve 33. The valves 33 for the several cylinders 30 may well receive air pressure from a main air line 34 which communicates with a pressure 85 tank 35, a suitable cutoff valve 36 being preferably provided in the piping 34. It will be seen that by turning the proper valve 33, any desired gates may be opened and the associated chute or chutes 8 simultaneously lowered to operative position.

I have shown pockets 3 at opposite sides of a track, but my invention may be used to equal advantage when the pockets are used at one side only of the track, in which instances, the links 27 at one end of the cross arms 28, the wheels 24 associated with said links, and adjacent gate-operating parts, may well be omitted. Two slotted guides 28^a are preferably employed for each cross arm 28, whether the latter operates gates at 95 opposite sides of the track, or a gate only at one side thereof, the cross arm having pins 28^b movable in certain slots of said guides.

It may be further explained that while only one pocket 3 at each side of the track has been shown discharging into the adjacent chute 8, it will be understood that any desired number of pockets might well discharge into one of said chutes. Furthermore, it may be explained that while I have described the invention for use in loading coal into cars upon an actual railway track, such invention is usable also for loading 110 rock or other materials either into cars, or into wagons or motor trucks, and in the latter instance, the roadway on which the trucks or wagons move, will of course take 115 the place of the track 1.

Excellent results may be obtained by the use of the invention in any of its forms and I wish it understood that the present disclosure is for illustrative purposes only, and that within the scope of the invention as 125 claimed, numerous modifications may be made. Also, it may be stated that any desired means may be provided for washing the coal as it is discharged from the pockets 3. For this purpose, piping 40 is shown, to 130

contain water under pressure, said piping being provided with valved branches 41 which discharge into coal spraying pipes 42 extending across the chutes. The valves 5 of the branches 41 may be connected with the disks 24, by links 43, so that said valves will be opened when the gates 6 are opened and will be closed upon closing of said gates. It may here be also stated that each 10 of the disks 24 is preferably provided with a plurality of openings which permit connection of any of the links therewith at the most advantageous point.

I claim:

15 1. In a coal car loading means, a coal pocket at one side of a car track having a gate for controlling discharge of coal, a vertically swingable chute into which said pocket discharges when the gate is opened, 20 said chute being adapted to direct the coal into a car to be loaded, a stationary pressure cylinder having a piston provided with a projecting piston rod, a cross arm to which said piston rod is secured, connecting means 25 between said cross arm and said gate for opening and closing the latter, connecting means between said cross arm and said chute for lowering the latter when the gate is opened and again raising said chute when 30 the gate is closed, and means for supplying fluid under pressure to either end of said cylinder.

2. In a coal car loading means, coal pockets at opposite sides of and above a car track, the inner walls of said pockets having 35 slidable gates for controlling the discharge of coal, a vertically swingable chute between said pockets into which they discharge when the gates are opened, said chute extending longitudinally over the track and being adapted when lowered to 40 guide the coal into a car to be loaded, a stationary cylinder mounted between said inner pocket walls and having a piston provided with a vertically projecting piston rod, a transverse cross arm secured on the end of said rod, stationary vertical guides for 45 said cross arm, links depending from the ends of said cross arm, wheels to which said links are eccentrically pivoted and means for supporting said wheels adjacent 50 said gates, other links connecting said wheels with said gates for controlling the latter, a suspending device depending from said cross arm to said chute for vertically moving the latter, and means for supplying fluid under pressure to either end of said cylinder.

3. In a coal car loading means, a coal pocket at one side of a car track having a gate for controlling discharge of coal, a vertically swingable chute into which said pocket discharges when the gate is opened, 60 said chute being adapted to direct the coal into a car to be loaded, a coal distributing

scraper carried bodily by the discharge end of said chute and adapted in lowered position to scrape off surplus coal when a car being filled is moved along the track after filling one portion of said car, and operating 70 means for said gate chute and scraper, including means for automatically lowering the chute and scraper when the gate is opened and for again raising said chute and scraper when the gate is closed.

4. In a coal car loading means, a coal pocket at one side of a car track, said pocket having a slideable gate controlling discharge of coal, a wheel mounted adjacent the gate and a link connecting it to said gate, a horizontal cross arm to which said link is pivoted, stationary vertical guiding means for said cross arm, a stationary vertical cylinder having a piston provided with a projecting piston rod secured to said cross arm, 80 and means for supplying fluid under pressure to either end of said cylinder.

5. In a coal car loading means, coal pockets at opposite sides of and above a car track, the inner walls of said pockets having 85 slideable gates for controlling the discharge of coal, a stationary cylinder mounted between said inner pocket walls and having a piston provided with a vertically projecting piston rod, a transverse cross arm secured on the end of said rod, stationary vertical guides for said cross arm, links depending from the ends of said cross arm, wheels to which said links are eccentrically pivoted and means for supporting said 90 wheels adjacent said gates, other links connecting said wheels with said gates for controlling the latter, and means for supplying fluid under pressure to either end of said cylinder.

6. In a coal car loading means, a coal pocket at one side of a car track having a gate for controlling discharge of coal, and a chute into which said pocket discharges when said gate is opened, said chute having a coal distributing scraper at its lower end adapted to be lowered into close relation with a car being loaded and operative to scrape off surplus coal when the car is moved along the track after filling one portion of said car.

7. A structure as specified in claim 6; said scraper comprising a pair of scraping members widely spaced at one end for disposition over the sides of the car, and converging substantially to a point at their other ends, said other ends of said scraping members being disposed at a higher point than the first named ends thereof when the scraper is lowered for use.

8. In a coal car loading means, a coal pocket at one side of a car track having a gate for controlling discharge of coal, a chute into which said pocket discharges when the gate is opened, said chute being

disposed longitudinally over the track, means pivotally supporting said chute to permit the discharge end thereof to be lowered into close relation with a car to be filled, and a coal distributing scraper carried bodily by said discharge end of said chute and adapted in lowered position to scrape off surplus coal when a car being filled is moved along the track after filling one portion of said car.

9. A structure as specified in claim 8; said scraper comprising a pair of scraping members widely spaced at one end for disposition over the sides of the car, and converging substantially to a point at their other ends, said other ends of said scraping members being disposed at a higher point than the first named ends thereof when the scraper is lowered for use.

10. In a coal car loading means, a coal pocket at one side of a car track having a gate for controlling the discharge of coal, a chute over said track into which the

pocket may discharge, said chute being disposed longitudinally over the track and having a coal distributing scraper at its discharge end, a pair of vertical bars between which the other end of said chute is pivoted on a horizontal axis, a pair of stationary vertical guides in which said bars are slidably received, and means for holding said bars in different adjusted positions in said guides.

11. In a coal car loading means, a pocket having a discharge gate, a rotatably mounted wheel adjacent said gate and connected with the latter for opening and closing the same, a coal washer disposed adjacent said gate and having a control valve, means connecting said control valve with said wheel for opening the same when the gate is opened, and means for turning said wheel.

In testimony whereof I have hereunto affix my signature.

ANDREW GERMEK.
